ADJUSTABLE PRICE MARK

Andrew Sommerville, Pasadena, Calif.

Application July 14, 1944, Serial No. 544,862

2 Claims. (Cl. 40—5)

1

This invention relates to an adjustable price mark and may be regarded as an improvement over my prior U. S. Letters Patent No. 1,413,500 issued April 18, 1922.

An object of the present invention is to provide an improved adjustable price mark wherein there is a front panel, a rear panel, and a supporting pedestal therefor, the rear panel having a plurality of leaves on which may appear characters or indicia indicative of the nature of the goods and the price thereof, and to provide means for releasably locking the front and rear panels together so that the uppermost leaves will be exposed through apertures or windows in the front panel. In this manner, by opening the panels and turning various leaves, adjustment of the device is permissible so that the nature or quality of the goods may be varied from time to time and the price thereof may likewise be varied from time to time.

More specifically, an object of the invention is to provide an adjustable price mark having the above mentioned characteristics wherein the rear panel and support are made integral with each other, facilitating manufacture and assembly of the device.

Another object of the invention is to provide an adjustable price mark wherein the support is hingedly connected to the back panel so as to be capable of assuming an inclined position to support the panels upright on a supporting surface, or the support may be caused to assume a substantially horizontal position so that it may be positioned on a floor stack display to support the panels against the side of the stack.

With the foregoing and other objects in view, which will be made manifest in the following detailed description and specifically pointed out in the appended claims, reference is had to the accompanying drawing for an illustrative embodiment of the invention, wherein,

Fig. 1 is a perspective view of the improved adjustable price mark embodying the present invention.

Fig. 2 is a partial view in perspective illustrating the front panel as having been detached from the rear panel and swung forwardly therefrom to expose the leaves for turning which are mounted on the back panel.

Fig. 3 is a vertical section taken substantially upon the line 3—3 upon Fig. 1.

Fig. 4 is a vertical section taken substantially upon the line 4—4 upon Fig. 2.

Fig. 5 is a sectional view taken substantially upon the line 5—5 upon Fig. 1.

2

Fig. 6 is a sectional view taken substantially upon the line 6—6 upon Fig. 1.

Referring to the accompanying drawing wherein similar reference characters designate similar parts throughout, the improved adjustable price mark comprises a front panel 10 which may be formed of cardboard, paperboard or the like and which has printed, mimeographed or otherwise displayed thereon, any ornamentation or advertising material that is to be permanently associated with the device. In this front panel there are formed one or more apertures or windows such as those indicated at 11 and 12. A back panel is provided indicated at 13 which underlies these windows and which carries a plurality of leaves or sets of leaves indicated at 14. Some of these leaves may bear numbers and signs indicative of the price, either in money or ration points. Others of these leaves may bear characteristics or indicia indicative of the volume, weight or quality. Leaves that bear numbers and signs indicative of the price are arranged in superposed relationship so that any leaf may be turned up or turned over to expose a subjacent 15 leaf or set of leaves bearing the numbers or signs of a different price. Similarly those leaves which bear indicia indicative of the volume, weight or quality may be arranged in superposed relationship and may be turned to expose any one of the 20 leaves through the corresponding window 11 to indicate any one of a number of different volumes, weights or qualities. The back panel preferably has integral therewith, a support 15 which is defined from an intermediate portion 16 such as 25 by score lines or fold lines 17. The back panel is also hingedly connected to this portion by such score lines or fold lines indicated at 18. Portion 16 is glued, stapled or otherwise secured to the back of the front panel 10. Near the bottom of 30 the back panel there is a split 19 adapted to receive a tongue 20 on the front panel to releasably lock the two panels together, wherein the windows or apertures are in registration with the leaves exposed thereby. In locking the two panels 35 in contiguous relationship, those leaves which have been pulled back are concealed by the front panel and are held in position thereby.

In some instances, as illustrated in Fig. 5, the leaves may be arranged in opposed groups so that 40 any upper leaf may be simultaneously exposed through the same window or opening with any leaf of the lower groove.

If the nature of the goods price-marked fluctuates from day to day, that is the quantity or 45 quality, leaves indicative of the quantity or 55

quality may be shifted in accordance with the fluctuations. Likewise if the price fluctuates from day to day, the leaves of the price group may be shifted or adjusted or turned back to expose the proper price through the window indicated at 12. When the adjustment has been made the front panel and back panel can be locked together by inserting the tongue 20 in the slit 19. Thereafter the support 15 may be swung to assume the inclined position as illustrated in Fig. 3, supporting the device on any suitable supporting surface. If desired, the support 15 may be caused to assume a horizontal position and be positioned, for example between the top and bottom of a stack of cans or other article so as to suspend or support the panels 10 and 13 upon the stack against the side of the stack. The front panel may be equipped with a hole 21 by which the entire device can be suspended from a nail or the like.

From the above described construction it will be appreciated that an approved adjustable price mark is provided which enables the front panel to have expensive lithographic work produced thereon economically, in that if the quantity, weight, or price of the commodity being advertised or price-marked varies, this may be designed by merely adjusting the leaves that are mounted on the back panel. Variation in these

variables do not involve a distortion or discarding of the front panel on which an expensive lithograph work may be produced.

Various changes may be made in the details of construction without departing from the spirit and scope of the invention as defined in the appended claims, wherein I claim:

1. An adjustable price mark comprising a front panel having window openings therein, a rear panel having foldable leaves secured thereto any one of which may be exposed through the window openings, and a support hingedly connected to the back of the front panel, said support being integral with the back panel, and an intervening portion between the support and the back panel defined from the back panel and support by fold lines and being secured to the back of the front panel.
2. An adjustable price mark comprising a front panel having window openings therein, a back panel hingedly connected to the front panel, a support hingedly connected to the front panel adjacent the top of the back panel, and means for detachably fastening the bottom of the front panel to the bottom of the back panel, said back panel having groups of leaves mounted thereon any one of which may be exposed through the window openings in the front panel.

ANDREW SOMMERSVILLE.
